Patented Feb. 28, 1928.

UNITED STATES PATENT OFFICE.

JAMES L. LOVE, OF LOS ANGELES, CALIFORNIA.

AUTOMATIC GARAGE-DOOR OPENER.

Application filed January 11, 1927. Serial No. 160,333.

This invention relates to a device for automatically opening or closing the door or doors of a garage. The general purpose of the invention is to provide a simple device 5 of this kind which will avoid the necessity for the driver of the car getting out of the car to open the door when he desires to run his car into the garage.

The general object of the invention is to 10 produce a simple device for this purpose and to construct the same so that it will operate not only to open the doors as the car passes into the garage but also to close them when the car withdraws from the garage.

15 To this end the invention includes means disposed in the path of a part of the automobile, and such means is duplicated, that is to say, I provide two members, alternately actuated one of which, when struck by the 20 car going in, opens the doors, and the other, struck by the car coming out, closes the doors. One of the objects of the invention is to support and guide these devices so that they operate alternately and so that one of 25 them will lie depressed and out of the path of the actuating part on the car when the other is elevated into its operating position.

A further object of the invention is to 30 provide simple means for supporting and actuating the garage doors.

Further objects of the invention will appear hereinafter.

The invention consists of the novel parts and combination of parts to be described 35 hereinafter, all of which contribute to produce an efficient automatic garage door opener.

A preferred embodiment of the invention is described in the following specification, 40 while the broad scope of the invention is pointed out in the appended claims.

In the drawing:

Figure 1 is a plan and partial section, certain parts being broken away, and illustrating 45 the apparatus as applied to a double door garage.

Figure 2 is a vertical section, broken away, taken about on the line 2-2 of Figure 1, and also illustrating the forward end of an 50 automobile, to indicate the manner in which it may operate the actuators to control the doors.

Figure 3 is a vertical cross-section taken on the line 3-3 of Figure 2.

55 Figure 4 is a front elevation of a portion

of the garage and illustrating the manner in which the garage doors are supported so as to enable them to swing open or closed. In this view certain parts are broken away.

Figure 5 is a fragmentary view showing a 60 plan of the upper end of the swivel post which supports each garage door, and showing a short portion of the supporting beam of the garage.

Figure 6 is a vertical section taken longitudinally of the driveway, and illustrating another embodiment of the invention as regards the means for actuating the doors.

In practicing the invention as applied to a double door garage, I provide a cross-head 70 1 which is mounted in a chamber or box 2 formed under the floor 3 of the garage.

Any suitable means may be provided for enabling this cross-head to swing the garage doors 4 open and closed, and in the present 75 instance, I provide a rack 5 at each end of the cross-head; each rack meshes with a pinion 6 which is secured to the pivot or pivot post 7 of the door. Below this pinion the swivel post of each door is mounted in 80 a suitable bearing 8 on the floor of the box. Each door 4 is provided with straps 9 that are riveted to each side of the door at its hinged edge, and the door is provided with a channel or recess 10 which receives the 85 post as indicated in Figure 1.

In order to actuate the cross-head 1, I provide a shifting bar 11 which is mounted to slide longitudinally in the driveway 12 90 of the garage.

I provide means for shifting this shifting bar inwardly when the car goes into the garage, so as to swing the doors open, and this means also operates when the car comes out of the garage, to swing the doors closed. 95

According to my invention I provide two actuators which are located in the path of a part of the car, or a bracket carried on the car axle. This apparatus will now be described. In the driveway I provide a chamber or box 13 in which I provide two actuators 14 and 15. These actuators are connected with the shifting bar 11, and I provide means for supporting and guiding them, which operates in such a way that when one of the actuators has been actuated by the car 16 it will be left by the car in a depressed position, while the other actuator will be left in an elevated position. In this way the actuators are made to operate alter- 100 105 110

- nately. As illustrated in Figure 2, each actuator consists of a bar which is guided to slide longitudinally through a transverse opening 17 in a rocker-bar 18. These rocker bars 18 are mounted transversely in the upper part of the box or chamber 13. Each of the actuator bars 14 and 15 is provided at its upper end with a head 19 of rubber or other resilient material, so as to reduce the shock when the end of the actuator is struck. The lower end of each actuator bar is connected by means of a yoke 20 and a pivot 21 with a split sleeve 22, which is clamped on the shifting bar 11.
15. Figure 2 represents the car 16 as though proceeding toward the garage. This car is provided with a bracket consisting of two vertical plates 23 attached to the forward axle 24 of the car. As the car moves toward the garage it will strike the upper end of the actuator 14 which at that time will be elevated above the upper end of the actuator 15. This will cause the actuator 14 to slide through the guide rocker 18 and shift the shifting bar 11 toward the garage. This will produce a corresponding movement in the racks 5 which, through their connection with the pinions 6, will swing the doors open. As this movement progresses, the head 19 will eventually move to a point below the path of the bracket 23, and the car will then pass over it and into the garage.
20. After the driver of the car comes out of the garage he can swing the garage doors closed by taking hold of them or he may operate the actuator 15 as a lever to close the doors.
25. The shifting bar 11 may be supported and guided by means of small guide rollers 25 disposed in an inclined position on opposite sides of the bar. This bar is of round form and the rollers are grooved so as to fit to the side of the bar. The lower portion of the box or chamber 13 has inclined side faces 26 to which the brackets carrying these rollers 25 are attached, see Figure 3.
30. In order to support each door 4, its pivot post 7 extends up through a beam 27 over the doorway, at which point each post is provided with a cross-pin 28. The ends of these pins may project beyond the post and carry rollers 29 which roll around on a washer or plate 30 resting on the upper face of the beam. If desired, however, where the ground is firm, or cement is provided, the weight of the door can be taken on the lower end of the post 7.
35. In Figure 6 I illustrate another embodiment of the invention in which the actuators are of a rocker type, instead of the form illustrated in Figure 2. In this type of actuator I provide two rock-levers 31 and 32. The lever 31 is the one that would be actuated by the car in passing into the garage.
40. A bracket or plate 33 on the car would strike the upwardly projecting arm 34 of this lever and swing it toward the left on its pivot pin 35. The lower end of the lever has a slot or groove 36, which engages a cross-pin 37 in a shifting bar 38.
45. In order to provide a cushion effect when the bracket 33 strikes the arm 34, I provide a pivoted bumper 39 on the upper end of the arm 34, that is pressed toward the right by a coil-spring 40. When the bracket 33 strikes the bumper 39, this spring 40, of course, is compressed, and in this way the jar of the sudden contact is yieldingly taken up by the rocker lever. The arm 34 has an off-set or lateral extension 41, the effect of which is to increase the vertical movement of the arm 34 when the arm is operated. This is desirable because it increases the vertical range of movement of the two rocker arms 31 and 32 with respect to each other and enables one to project to a considerable elevation above the other in the alternating movements of the two rocker arms.
50. The construction of the rock-lever 32 is substantially the same as that of the rock-lever 31 except that one is a right-hand lever and the other a left-hand lever. In other words, the upper arm 42 of the rock-lever 32 is offset to the right by means of a lateral extension 43. This rock-lever 32 is rocked on its pivot pin 44 when the car moves out of the garage, by engagement with the bracket-plate 33 moving toward the right, as viewed in Figure 6. The upper end of this arm 42 has a bumper 45 similar in construction and function to the bumper 39, and pressed toward the garage by a spring 46.
55. Figure 6 shows the arm 34 partially depressed, as it would be when the garage doors are partially open. As the movement progresses the arms 34 will be depressed sufficiently to permit the plate 33 to pass over it, as the car passes into the garage. This will leave the arm 34 in a depressed position while the arm 42 will be considerably elevated. When the car comes out of the garage the plate 33 will strike the bumper 45, and the operation just described will be reversed; that is to say, the shift bar 38 will be moved inwardly instead of outwardly and the arm 42 will become depressed as the bracket 33 passes over it with the car.
60. With this rocker type of actuator, the construction of the cross-head 1 would be the same as illustrated in Figure 1, except that the racks 5 would be located on the adjacent sides of the pinions 6 instead of on their outer sides.
65. The arms 34 and 42 extend up through slots 47 in the upper side of the box or housing 48, that houses the levers, and are located at the surface 49 of the driveway. These slots may be covered by sliding plates 50 which, if desired, may carry rollers 51 on their under sides. These plates 50 com-

pletely cover the slots and assist in keeping rain water out of the box.

It is understood that the embodiment of the invention described herein is only one of the many embodiments this invention may take, and I do not wish to be limited in the practice of the invention, nor in the claims, to the particular embodiment set forth.

What I claim is:

- 10 1. In an automatic garage door opener, the combination of a door mounted to swing on a vertical axis, a bar guided to slide longitudinally toward or from the garage door and located in the driveway, actuating means mounted in the driveway having two actuating members on the same side of the garage door projecting up to a point in the path of the front axle of the automobile so as to be struck alternately by the automobile front axle as it passes in and out, means connecting the actuator with the said bar to shift the bar longitudinally, and means connecting the bar with the door to swing the door open.
- 25 2. In an automatic garage door opener, the combination of a door mounted to swing on a vertical axis, a bar guided to slide longitudinally toward or from the garage door and located in the driveway, an actuator mounted in the driveway and projecting up to a point in the path of the front axle of the automobile so as to be struck by the automobile as it passes, means connecting the actuator with the said bar to shift the bar longitudinally, means connecting the bar with the door to swing the door open, and a second actuator connected with the first actuator so as to be moved to an elevated position when the first actuator is depressed by the axle, and connected with the bar to move the same in the opposite direction to close the door.
- 35 3. In an automatic garage door opener, the combination of a door mounted to swing on a vertical axis, a bar guided to slide longitudinally toward or from the garage door and located in the driveway, an actuator mounted in the driveway and projecting up to a point in the path of the front axle of the automobile so as to be struck by the automobile as it passes, means connecting the actuator with the said bar to shift the bar longitudinally, means connecting the bar with the door to swing the door open, and a second actuator on the same side of the

garage door as the first actuator movable in the opposite direction from the first actuator, connected with the bar to move the same in the opposite direction to close the door, and means for supporting and guiding said actuators so that when one is in an elevated position the other is depressed, enabling the same to operate alternately to open and close the garage door.

4. In an automatic garage door opener, 65 the combination of a pair of garage doors mounted to swing on a vertical axis, a cross-head with means connecting the same with the garage doors to swing the same open when the cross-head is actuated, a bar connected with the cross-head and extending longitudinally in the garage driveway, an actuator connected with the bar for shifting the same inwardly, and adapted to be struck by a bracket on the axle of the automobile 70 when passing into the garage, a second actuator connected with the bar for shifting the same in an outward direction and adapted to be struck by a bracket on the axle of the automobile as it comes out of the garage, 75 and means for supporting and guiding said actuators so that when either of them is elevated the other is depressed.

5. In an automatic garage door opener, 85 the combination of a post disposed on each side of the garage doorway, means for supporting the post to enable the same to turn on its longitudinal axis, a garage door secured to each post, a pinion rigid on each post, a cross-head having a rack meshing 90 with the outer side of each pinion, a shifting bar attached to the cross-head and mounted to slide longitudinally in the garage driveway, an actuator attached to the bar for shifting the same inwardly to open the 95 garage doors and projecting upwardly so as to lie in the path of a bracket carried by the axle of the car, a second actuator connected with the shifting bar and projecting upwardly so as to be in the path of a 100 bracket carried by the car's axle for shifting the bar in an outward direction to close the garage doors, and means for supporting and guiding the actuators so that they operate alternately, one of the said actuators 105 being depressed when the other is elevated.

Signed at Los Angeles, Calif., this 30th day of December, 1926.

JAMES L. LOVE.
